UNITED STATES PATENT OFFICE.

JOHN L. BECK, OF SPRINGFIELD, MASSACHUSETTS, ASSIGNOR TO THE AUTO SAFETY CRANK COMPANY, OF HOLYOKE, MASSACHUSETTS, A CORPORATION OF MASSACHUSETTS.

SAFETY CRANKING DEVICE FOR EXPLOSIVE-ENGINES.

1,027,799.

Specification of Letters Patent.

Patented May 28, 1912.

Application filed March 20, 1911. Serial No. 615,676.

To all whom it may concern:

Be it known that I, JOHN L. BECK, a citizen of the United States of America, and resident of Springfield, in the county of Hampden and State of Massachusetts, have invented certain new and useful Improvements in Safety Cranking Devices for Explosive-Engines, of which the following is a full, clear, and exact description.

10 This invention relates to improvements in safety cranking devices for explosive engines of a kind having for its object the preventing of any possible injury to a person while cranking up by reason of a back kick which might ensue when the engine shaft from any cause acquires a forcible reversed rotation.

20 The aim of the present invention is to provide a safety crank which while entirely reliable and effective under all conditions is extremely simple by reason of comprising only comparatively few parts and is, moreover, comparatively inexpensive of production because of the facility and practicability of construction.

Another object is to increase the safe-guarding characteristics by the provision of means whereby in case the engine shaft starts running forwardly and the starting 30 or cranking shaft fails to be thrown out of clutch with the engine shaft as is usually expected, the crank while being held by the hand cannot be thrown around forwardly to do violence to the person who may be 35 operating it.

The invention is described in conjunction with the accompanying drawings and is set forth in the claims.

In the drawings:—Figure 1 is a side elevation of the safety crank as combined for use relatively to an engine shaft and to a part of a structure in conjunction with which the engine shaft is employed. Fig. 2 is a longitudinal sectional view centrally through the 40 cranking device, with the parts thereof out of clutch. Fig. 3 is a plan view of the mechanism of the cranking device with the parts thereof shown as in clutch, the inclos-

ing crank hub and certain other parts being represented in sectional view. Figs. 4, 5, 6 50 and 7 are cross sectional views as taken respectively on the section lines 4—4, 5—5, 6—6, and 7—7, of Fig. 2 looking in the direction of the arrows. Fig. 8 is a perspective view showing all of the components of 55 the device in separated relation.

The cranking device forming the subject of this case is of the same general type as those shown in my co-pending applications, Serial Numbers 590,687 and 610,483, filed, 60 respectively, November 4, 1910, and February 24, 1911.

In the drawings, A represents in Fig. 1 a small portion of the engine shaft having the ratchet toothed clutch member A² thereon, as usual; and B represents the cranking or starting shaft having at the rear end thereof the clutch member B² to be thrown by actual movement against its spring B³ into engagement with the clutch member 70 A² so that by the turning of the crank C in the usual forward direction, the engine shaft will be rotated for the starting of the engine. The cranking shaft B has affixed on its forward end the flange like clutch member D provided with rearwardly facing teeth a; and E represents a companion clutch member which is rotatively free and axially movable within comparatively slight 75 limits on the cranking shaft, and in proximity to the shaft carried clutch member E; and the clutch member E has forwardly facing clutch teeth b for engagement with the teeth a.

F represents a sleeve like member frictionally engaged with the cranking shaft by means of the split tapered shell d which encircles the shaft constrictively and has a disposition for the greater portion of its length within the flaring orifice of the 90 passage through the sleeve. The sleeve, moreover, has at its forward end an outwardly projecting flange e and has on its forward end face a plurality of cam surfaces, one of which is shown at f in Fig. 3, 95 while these cam surfaces are also represented

in Figs. 2 and 8. The sleeve is also at its rear end portion provided with peripheral teeth g ,—such toothed portion being encircled by a collar G which has on an arm-like extension h thereof a rigid dowel like part h^2 which is engaged slidably through a bracket h^3 mounted on or provided as a fixture of the body of the automobile or frame of the machine comprising the engine.

i represent pawls mounted in the encircling collar and engaging the teeth g of the sleeve which, as before stated is frictionally engaged upon the cranking shaft so that in case of any backward rotation of the cranking shaft tending to produce a back kick, the pawls prevent the sleeve from being carried around in a rearward direction with the shaft. The specific form of the spring pressed pawl i and of the teeth g here shown are approved ones found advantageous and satisfactory in actual use; but other pawl and ratchet devices of specifically different character could be employed.

J represents the hollow cylindrical hub of the crank C , the same opening rearwardly and having a front end closing wall j . This hub when combined with the other parts of the mechanism incloses the clutch members D and E and a considerable portion of the sleeve F , as well also as an annular member L which is carried therewithin and as an appurtenance thereof. The said annular member may be regarded in a sense as an internal flange of the hub; it is freely rotative but axially non-movable relatively to the shaft, and has its location between the forward end of the sleeve and the movable clutch member E . It is to be noted that the movable annular clutch member E has at its rear face the shoulders k with separating spaces k^2 between them; and the annular member L has forwardly protruding shoulders m with separating spaces m^2 between them so that there is an interlocked lost motion giving engagement between the two sets of spaced shoulders, such lost motion rotatively of the one member relatively to the other being permitted because of the fact that the widths of the shoulders m m are less than the spaces k^2 between the shoulders k of the movable clutch, and springs n are interposed between the shoulder interlocking portions, tending to force the movable clutch member E slightly rotatively forwardly relatively to the annular crank driven element L .

The annular member L has holes o therethrough on lines parallel with the axis of the device in which are fitted slideable pins or dogs p which protrude rearwardly for engagement with the cams f on the forward end of the sleeve F and have their forward

ends in engagement with the rear face of 65 the movable clutch member E .

The annular member L instead of being rigidly secured within the hub of the crank as it might be for good action generally, is engaged with the crank hub by means of 70 the pawls q which engage with the peripheral teeth r of the part L ,—the forms and arrangements of these coating parts or features being such that when the crank is turned in the proper forward direction, as 75 indicated by the arrow x , Fig. 5, the element I will pull as one with it; but on relatively reversed forces being applied, that is if from any cause the annular member L should acquire rotation in the direction of the arrow 80 faster than that imparted in such direction manually by the crank, the pawls would recede and permit the part L to click around in the crank hub. This last described provision is one to safeguard against harm to 85 a person in case the crank shaft fails to be automatically thrown out of clutch with the engine shaft when the latter shaft starts running forwardly as usually transpires.

The ring nut s is screw engaged on the 90 rear extremity of the sleeve next to the collar G , and another ring nut t has a screw engagement with the cylindrical crank hub and engages the rear face of the flange of the sleeve, and an inspection of Fig. 2 will 95 indicate without the necessity of further extended description the manner in which all of the parts are held together and maintained in their proper operative relations,—it being, however, mentioned that the spacing sleeve u which encircles the cranking shaft is interposed and engages by its opposite end the annular element L and the shaft carried clutch member D .

The spiral spring M is interposed in an 105 encircling relation to the spacing sleeve u and in compression between the shaft affixed clutch member D and the movable clutch member E with the effect of exerting a force rearwardly on the movable clutch member 110 and serving as a means for the increased reliability and certainty of action of the device when the emergency calls for the same.

Respecting the operation:—Assuming the 115 parts of the crank are in their disengaged position as represented in Fig. 2, and the dogs or thrust pins p have positions to the right with their extremities in the most depressed portions of the cams f , in cranking 120 the engine the crank is turned in a forward direction with the effect of carrying the annular member around with it, and as such annular member can have no axial motion, its pins p will be necessarily slid forward 125 or to the left with the effect of exerting a thrust against the axially movable clutch member E for throwing it into clutch with

shaft carried clutch member D; and if the teeth of the two clutch members should be brought into point to point relation, the clutch member which has a degree of spring 5 retracted lost motion revolubly relatively to the annular member, will readily find its bottoming into the other clutch member, the annular member L being, as before stated to all intents and purposes in the cranking 10 forward a fixed part of the crank, and being interlocked with the movable clutch member E which is thrown into interlock with the fixed clutch member D, the cranking shaft and all the parts combined there- 15 with except the collar G turn in unison with no different effect than if the crank was the same as the ordinary simple fixed crank on a cranking shaft. In case of a back kick whereby the cranking shaft would be driven 20 reversely, the pawls i hold the sleeve member from having any rotation, and the fixed clutch member D turning with the back kicking shaft has a movement relatively to the annular member and movable clutch member 25 which are held against turning by reason of the hand grasp on the crank handle so that any tendency which the shaft carried clutch member D has to carry the movable clutch member E and crank carried annular mem- 30 ber L around with it in the reversed direction is effective to slightly rotate the movable clutch member, but yet in a sufficient extent to allow the dogs to come opposite the depressed surfaces of the cams formed 35 on the end of the sleeve, and at this time, owing to the shape of the clutch teeth; and further because of the reaction of the spiral spring, the two members of the clutch are thrown out of engagement, leaving the 40 crank and its hub, the annular member and the movable clutch member therewithin to be retained by the hand grasp as parts relatively to which the cranking shaft and its clutch have no connection.

45 I claim:-

1. In combination, a cranking shaft having a clutch member fixed thereon, a companion clutch member rotatively free and also axially movable on the shaft, a sleeve 50 frictionally engaged with the shaft for rotation with the same in one direction, said sleeve having cam surfaces thereon, means for holding the sleeve against reversed rotative movement, an annular member freely 55 rotative on said shaft but axially non-movable, said annular member being located between the sleeve and the axially movable clutch member and having an interlocking relation to the latter, dogs carried by said 60 annular member and arranged for impingement on said cam surfaces, which dogs are operable by end thrust against the said movable clutch member to force it into engagement with the fixed clutch member

when said annular member is forwardly ro- 65 tated, and means for rotating the said annular member.

2. In combination, a cranking shaft having a clutch member fixed on its forward end, a companion clutch member rotatively free and also axially movable on the shaft and having rearwardly projecting shoulders, a sleeve frictionally engaged with the shaft for rotation with the same in one direction, 70 said sleeve having cam surfaces on its forward end, means for holding the sleeve against reversed rotative movement, and a crank having a hollow hub carrying there- 75 within an annular member which is freely rotative on said shaft but axially non-mov- 80 able, said annular member being located between the sleeve and the axially movable clutch member and having forwardly projecting shoulders arranged for a lost motion interlocking relation to the shoulders on said 85 clutch member, and having dogs arranged for impingement on said cam surfaces and operable by end thrust against the said movable clutch member to force it into engagement with the fixed clutch member under 90 a forward rotation of the crank.

3. In combination, a cranking shaft having a clutch member affixed thereon, a companion clutch member rotatively free and also axially movable on the shaft, a sleeve 95 frictionally engaged with the shaft for rotation therewith in one direction, said sleeve having cam surfaces on its end, means for holding the sleeve against reversed rotative movement, a crank having a hub carrying 100 therewithin an annular member freely rotative but axially non-movable relatively to the shaft and located between the sleeve and the axially movable clutch member, said annular member having a lost motion inter- 105 locking relation to the latter and having dogs arranged for impingement on said cam surfaces and operable by end thrust against the said movable clutch member to force it into clutch under a forward rotation of the 110 crank, and a spring exerting an axially rearward pressure upon the movable clutch member.

4. In combination, a cranking shaft having a clutch member affixed thereon, a companion clutch member rotatively free and also axially movable on the shaft and having at its rear face shoulders with separating spaces between them, a sleeve frictionally engaged with the shaft for rotation 115 therewith in one direction, said sleeve having cam surfaces on its forward end, means for holding the sleeve against reversed rotative movement relatively to the shaft, a crank provided with a hollow hub having 120 therein an annular member freely rotative but axially non-movable relatively to the shaft and located between the sleeve and the

axially movable clutch member and having forwardly protruding shoulders with separating spaces, the spaces between the shoulders on one member being greater than the widths of the shoulders on the adjacent member, springs interposed between the interlocking shouldered portions, and a pin carried by said annular member longitudinally slidably relatively thereto and coacting with the cam on the sleeve and the movable clutch member.

5. In combination, a cranking shaft having a flange like member fixed on its forward end provided with rearwardly facing clutch teeth, a companion clutch member rotatively free and also axially movable on the shaft and having forwardly facing clutch teeth, a sleeve member frictionally engaged with the shaft for rotation therewith in one direction, said sleeve having cam surfaces on its forward end provided, peripherally, with teeth, a collar held against rotative movement encircling the sleeve and having pawls in engagement with the teeth of the latter, a crank having a hub carrying therewithin an annular member freely rotative but axially non-movable relatively to the shaft and located between the sleeve and the movable clutch member, said annular member having an interlocking lost motion relation to such clutch member and carrying axially slidable pins arranged for coaction, between the sleeve cams and the movable clutch member, and a spring for forcing the movable clutch member away from the fixed clutch member.

6. In combination, a cranking shaft having a flange like member fixed on its forward end and provided with rearwardly facing clutch teeth, a companion clutch member rotatively free and also axially movable on the shaft and having forwardly facing clutch teeth, a sleeve member frictionally engaged with the shaft for rotation therewith in one direction, said sleeve having cam surfaces on its forward end and provided, peripherally, with teeth, a collar held against rotative movement encircling the sleeve and having pawls in engagement with the teeth of the latter, a crank having a hub carrying therewithin an annular member freely rotative but axially non-movable relatively to the shaft and located between the sleeve and the movable clutch member, said annular member having an interlocking lost motion relation to such clutch member and carrying axially slidable pins arranged for coaction between the sleeve cams and the movable clutch member, and interengaging teeth and pawls provided upon said annular member and crank hub whereby the forward turning movement of the crank hub will cause said annular member to turn therewith in the same direction, and whereby when a forward movement is im-

parted to the annular member independently 65
of the crank hub, said annular member will
be permitted to turn free of said hub.

7. In combination, an engine shaft and a cranking shaft having coacting clutch members, the cranking shaft having a movement endwise relatively to the engine shaft, a spring for forwardly forcing the cranking shaft, a clutch member fixed on the forward end of the cranking shaft, a companion clutch member rotatively free and axially movable on the cranking shaft, a sleeve frictionally engaged with the cranking shaft for rotation therewith in one direction, said sleeve having cam surfaces on its forward end and having peripheral teeth, a collar encircling the toothed portion of the sleeve provided with pawls and having a dowel extension, a fixed part with which the dowel extension has a sliding engagement, a crank having a hub carrying therewithin an annular member freely rotative but axially non-movable relatively to the shaft and located between the sleeve and the movable clutch member, said annular member having an interlocking and lost motion relation to the latter and having pins slideable relatively thereto and arranged for coaction between the cam surfaced end of the sleeve and the movable clutch member, and a spring for forcing the movable clutch member away from the fixed clutch member. 95

8. In combination, a cranking shaft, a clutch member fixed on the forward end thereof, a companion clutch member relatively free and axially movable on the cranking shaft, a sleeve frictionally engaged with the cranking shaft having cam surfaces and an outwardly extending flange at its forward end and having peripheral teeth, a non-rotative collar encircling the toothed portion of the sleeve provided with pawls, a ring nut screwing on the rear extremity of the sleeve next to the collar, a crank having a hollow hub carrying therewithin an annular member which is freely rotative but axially non-movable relatively to the shaft and is located between the sleeve and the movable clutch member, said annular member having an interlocking and lost motion giving relation to the latter and having pins slideable relatively thereto and arranged for coaction between the cam surfaced end of the sleeve and the movable clutch member, a spring for forcing the movable clutch member away from the fixed clutch member, and a ring nut screwed on the crank hub next to the rear face of the flange of the sleeve.

9. A cranking shaft having fixed and movable clutch members mounted upon its forward portion, a sleeve frictionally engaged with the shaft rearwardly of said clutch members, a one-way ratchet clutch

coacting with the sleeve for preventing backward rotation thereof, an annular body incasing said fixed and movable clutch members, and means carried within said body between said sleeve and said movable clutch member for coaction with the same, to cause said movable clutch member to engage said fixed clutch member when said body is turned forwardly, and to cause said mov-

able clutch member to disengage said fixed 10 clutch member upon a reversed movement of said shaft relative to said body.

Signed by me at Springfield, Mass., in presence of two subscribing witnesses.

JOHN L. BECK.
